PUNCHING ATTACHMENT FOR PRESSES

Filed Dec. 14, 1927

UNITED STATES PATENT OFFICE

WILLIAM H. NICKERSON, OF NEWTON, MASSACHUSETTS

PUNCHING ATTACHMENT FOR PRESSES

Application filed December 14, 1927. Serial No. 239,897.

The object of this invention is to provide a 5 punching attachment insertible as a unit between the fixed bed and movable platen of a press, and having male and female punch members, adapted to punch holes in a metal strip inserted between the bed and platen, the attachment or unit being adapted to be used interchangeably with other like attachments or units, having differently arranged 10 punch members, so that the press may be adapted to punch differently arranged holes by substituting one attachment or unit for another.

Other objects will appear hereinafter. 15 Of the accompanying drawings forming a part of this specification,

Figure 1 is a side view of a punching attachment embodying the invention, separated from a press, portions at one end of the 20 attachment being shown in section.

Figure 2 is an end view of the attachment.

Figure 3 is a section on line 3-3 of Figure 1.

Figure 4 shows an end view of the attachment and sectional views of portions of a 25 press bed and platen between which the attachment is interposed.

Figure 5 is a perspective view of one of the male punch member holders.

30 Figure 6 shows in perspective portions of the compound guide hereinafter described.

Figure 7 is a fragmentary sectional view, showing the coaction of the punch members.

35 Figure 8 is a view similar to Figure 6, showing a modification.

The same reference characters indicate the same parts in all of the figures.

In the drawings, my improved attachment 40 shown separately by Figures 1, 2 and 3, includes a base 12, which is a metal plate or block, separably attachable to a bed 13 of a press, and a head 14, which is a metal plate or block, adapted to bear separably on the 45 platen 15 of the press.

The platen and bed may be members of a press of any suitable construction, the platen being movable toward and from the bed.

Any suitable means may be provided for 50 separably attaching the base to the platen,

so that different attachments embodying the invention may be used interchangeably.

The bed 13 shown by Figure 4, is provided with a seat 16, on which the base 12 is seated, and ears 17 and 18 at opposite edges of the 55 seat. The ear 18 is undercut and engages a beveled side face of the base. The ear 17 is provided with set screws 19, engaging the opposite side face of the base, the arrangement being such that the base may be removed from the bed when the set screws are loosened. When the platen 15 is raised, it is separated from the bed sufficiently to permit the interposition of the attachment between the bed and platen. 60

The base 12 is provided with female punch members 20, of which there are three in this instance, arranged in tandem order, said members being inserted in vertical sockets 21, formed for their reception in the bed. Outlets 22 are provided below the sockets for the escape of blanks punched from a work strip 24 (Figure 4) positioned above the punch members 20. 65

Attached to the upper surface of the base 70 is a compound guide forming, with the base, a horizontal channel 26, adapted to horizontally guide the work strip and prevent upward displacement thereof when the male punches, described later, are withdrawing 75 from the strip.

The compound guide is preferably composed of two parallel members 25 (Figure 6), attached edge to edge to the base by screws, and provided with offset inner edge 80 portions 250, forming the sides and top of the channel 26. In the edge portions 250 are formed a plurality of pairs of substantially semicircular recesses collectively constituting vertical guide openings 251, of 85 which there are three in this instance, said openings communicating with the channel 26 and being adapted to vertically guide the holders of the male punches described later. The compound guide may be made in a single 90 piece, as shown by Figure 8, having an offset central portion 250^a forming the sides and top of the channel and provided with circular openings 251^a for the same purpose as the openings 250. 95

Any suitable means may be provided for guiding the head 14 in a predetermined path relative to the base, and maintaining the head parallel with the base, such means being preferably embodied in studs 27, fixed as by set screws 28 to the head, and slidably in guiding orifices 29 in the base.

To support the head yieldingly retracted from the base, I provide means, preferably embodied in springs 30, interposed between the base and head and surrounding the studs 27.

To limit the retraction of the head from the base, I provide stop means, preferably embodied in upwardly projecting stops 31, fixed as by screws or bolts 32 to opposite ends of the base, and upwardly facing ears 33, formed on the head 14 and normally held by the springs 30 against stop shoulders 33a on the stops 31.

Fixed to the head 14, as by set screws 39, are tubular male punch holders 36, holding male punch members 34, the holders being preferably split at one end, as shown at 37 (Figure 5), and adapted to be clamped by the set screws on the members 34. The holders 35 are arranged to enter and be guided by the guiding openings 251, as shown by Figure 7, when the head is projected. The punch members 34 have a limited projection from the holders 36, and are guided by the holders and the guiding openings 251 in exact alinement with the female member 20, so that there is no liability of misalinement, the limited projection of the male members from the holders preventing liability of lateral displacement of said members.

The stop members 31 are, in this instance, formed to extend across the ends of the compound guide, and provided with orifices 40, through which the work strip 24 is movable.

It will now be seen that an attachment having a predetermined arrangement of punch members may be quickly and conveniently removed from a press, and another having a different arrangement of punch members substituted therefor, the vertical movement of the press platen being such that each descent of the platen causes the coaction of the punch members.

Figure 4 shows auxiliary means cooperating with the springs 30 to retract the head 14, and prevent the male punch members from sticking in the work strip, said means comprising a lever 41, fulcrumed at 42 to a fulcrum member 45, attachable as by screws 46 to the press bed, one arm of the lever bearing on the head, and a spring 43, fixed at one end to the other arm, and at its opposite end to a fixed holder 44, the arrangement being such that the spring is tensioned by the descent of the platen, and acts to retract the head when the platen rises. The lever, the fulcrum member, and the spring 43, constitute an element of the attachment which may

be connected with the press bed, after the base 12 is attached to the bed.

I claim:

A punching attachment insertible as a unit between the bed and platen of a press, and comprising a base adapted for separable attachment to a press bed, and provided with female punch members and with means for guiding and positioning a work strip relative to said members, a head adapted to bear separably on a press platen and be projected thereby and provided with male punch members complementary to the female members, springs interposed between the base and head and normally holding the head retracted from the base, complementary stop members on the base and head, limiting the retraction of the head, the base and head being provided with complementary members for guiding the head, and auxiliary means for retracting the head, said means including a fulcrum member adapted to be secured to a press bed, a two-armed lever fulcrumed to said member, and a spring connected with one arm of the lever and with a fixed holder, and pressing the other arm against the head.

In testimony whereof I have affixed my signature.

WILLIAM H. NICKERSON.
